UNITED STATES PATENT OFFICE.

ANTONIO REA, OF BOSTON, MASSACHUSETTS.

GRAPHOPHONE AND LIKE MACHINE.

Application filed April 24, 1922. Serial No. 556,183.

To all whom it may concern:

Be it known that I, ANTONIO REA, a citizen of the United States, residing in Boston, in the county of Suffolk and State of Massachusetts, have invented an Improvement in Graphophones and like Machines, of which the following description, in connection with the accompanying drawings, is a specification, like characters on the drawings representing like parts.

This invention relates to graphophones and like machines in which a stylus carried by a tone arm cooperates with a record disk mounted on a turntable, and has for its object to provide machines of the character described, with a brake for the turntable, which is controlled by the tone arm, so as to be released when the tone arm is moved into one position and to be applied when the tone arm is moved into another position.

The invention further has for its object to provide for operating the brake with the tone arm in different positions, as will be described, whereby the brake may be operated when record disks of different sizes or diameters are used on the machine.

These and other features of this invention will be pointed out in the claims at the end of this specification.

Fig. 1 is a plan view of a sufficient portion of a graphophone embodying this invention to enable it to be understood, the tone arm being shown in its extreme positions.

Fig. 2, a side elevation of Fig. 1 looking toward the left, with the turntable in section.

Fig. 3, a detail to be referred to.

Fig. 4, a plan view of the brake mechanism in its released or inoperative position and locked therein.

Fig. 5, a detail in section on the line 5—5, Fig. 4, and

Fig. 6, a detail in section on the line 6—6, Fig. 4.

In the present instance, one embodiment of the invention is shown which is applied to a graphophone of known construction, of which *a* represents the turntable, *b* the record disk thereon, *c* the tone arm, and *d* the stylus carried by the tone arm.

The tone arm *c* has connected with it a device for controlling the operation of a

brake mechanism which cooperates with the turntable. One construction of brake mechanism is shown, which comprises a lever or member 10 carrying a leather or other non-metallic pad 12 for engaging the inner surface of the flange 13 on the turntable *a*. The lever 10 is pivoted at 14 to a supporting frame or bar 15, which is located below the turntable and is secured to the box or cabinet 16 of the machine, which is represented in Fig. 2.

The brake lever or member 10 is directly actuated by an arm 17 having a slot 18 into which is extended a pin 19 on the brake lever 10. The arm 17 is fixed to a rod or bar 20 slideable in guides 21, 22, attached to the stationary frame or bar 15. The slideable bar 20 has an extension in the form of a rod 23, which in the present instance is pivotally connected with a disk 24 mounted to turn on a pin 25 attached to the stationary frame 15. The disk 24 is provided with a slot 26 through which the pin 25 is extended and which permits the disk to slide on the supporting bar 15 for a purpose as will be described.

The disk 24 is provided with a wedge shaped stud or pin 27 which is adapted to be engaged by a device movable with the tone arm *c* to effect movement of the brake actuating bar 20 so as to remove the brake member 10 from engagement with the turntable *a*. The bar 20 is moved in the opposite direction to engage the brake member 10 with the turntable *a* by a spring 29, which encircles the sliding bar 20 and has one end connected therewith and its opposite end engaged with the guide 22.

As herein shown, the spring 29 is compressed when the bar 20 is moved in the direction of the arrow 30 in Fig. 1 to throw off or release the brake and render the turntable free to be revolved, which in the machines of this character now on the market is usually effected by a spring motor, not shown. Provision is made for locking or holding the brake actuating member or bar 20 when the brake is in its released or inoperative position. To this end, the bar 20 is provided with an inclined surface 32, which constitutes a catch, with which cooperates the V-shaped end of an arm or dog 33 attached to a lever 34 and guided by a pin

35 is extended into a slot 36 in the said dog. The pin 35 is attached to the supporting frame or bar 15 and the lever 34 is pivoted at 37 to a bracket or arm 38 attached to said 5 frame or bar 15.

The lever 34 is acted upon by a spring 39 which serves to keep the dog 33 in engagement with the catch 32, as represented in Fig. 4, and thus hold or lock the brake 10 10 in its disengaged or released position while the record *b* is being played.

Provision is made for disengaging the locking dog 33 from the catch 32 by the device carried by the tone arm. To this end, 15 the lever 34 is provided with a pin or stud 40 with which cooperates the device carried by the tone arm, so that the lever 34 may be turned against the action of the spring 39 to withdraw the locking dog 33 20 from engagement with its catch 32 and permit the spring 29 to move the rod 20 in the direction opposite to that indicated by the arrow 30, and through the arm 17 and pin 19 turn the brake member 10 so as 25 to engage its member or pad 12 with the turntable, and thus stop the turntable.

The device connected with the tone arm may be made as herein shown, and consists 30 of an arm or lever 43 frictionally clamped by disks 44, see Fig. 3, to an arm 45 on a split ring or collar 46, which is engaged with the tone arm *c* and is secured thereon to move therewith by a screw 47 and nut 48, said screw passing through ears 49 at 35 the free ends of the collar and having a spring 50 thereon between said ears.

The arm 43 is capable of being turned by the operator on the pin 51, upon which the friction washers or disks 44 are mounted, for purposes of adjustment, as will be 40 described, and when adjusted the friction created by the disks 44 is sufficiently great to render the arm 43 practically stationary on the arm 45 for brake operating purposes. The arm 43 is designed to cooperate 45 with a stop or pin 52 on the supporting member 15, when the tone arm *c* is in its extreme outward position with the stylus *d* beyond the turntable, as shown by dotted lines in Fig. 1. The arm 43 is also designed 50 to engage the pin 40 on the lever 34 and move the latter so as to trip the locking device or dog 33 for the brake mechanism and allow the brake to be applied by the 55 spring 29 at or about the time the tone arm *c* reaches its extreme inner position with the stylus *d* at the end of the record.

By reference to Fig. 1, it will be seen 60 that the arm 43 turns with the tone arm *c* in a circular path from the fixed stop 52 to the movable stop 40; that it is moved from the fixed stop 52 toward the movable stop 40 with the tone arm *c* under the influence of the record *b*; and is moved in 65 the opposite direction by the operator when

he turns the tone arm back into its inoperative position represented by full lines in Fig. 1.

On the backward movement of the tone arm *c* the arm 43 engages the front edge 70 or apex of the stud or projection 27 and causes the disk 24 to be turned in the direction indicated by the arrow 54 until the brake actuating bar 20 has been moved sufficiently to carry the catch 32 beyond the 75 end of the locking dog 33, which allows the spring 39 to move the tripping lever 34 toward the bar 20 and bring the locking dog 33 into the path of the catch 32. If the tone arm should be released at 80 this time the brake would be locked in its released position as shown in Fig. 4, in which position the arm 43 is in front of the stud 27, and the tone arm is at such time over the turntable with the stylus over 85 the record. To permit the brake to be applied to the turntable, the tone arm is still further moved in the same direction, and in this further outward movement, the arm 43 turns the disk 24 still further in the direction of arrow 90 54 until the arm 43 is disengaged from the stud 27 and is engaged with the fixed stop 52.

During the movement of the arm 43 from 95 in front of the stud 27 to the position in rear of said stud, the rod 20 is further moved in the direction indicated by the arrow 30 and still further compresses the spring 29 and increases the power of the same sufficiently to overcome the spring 39 100 and move the bar 20 in the direction of the arrow 56 to apply the brake to the turntable, at which time the tone arm overhangs the turntable as represented by dotted lines in Fig. 1.

The increased power of the spring 29 is sufficient to carry the beveled latch 32 past the beveled face of the dog 33 against the action of the spring 39.

It will thus be seen that in the inoperative 110 position of the tone arm, with the stylus overhanging the turntable, the latter is held stationary by the brake, and the arm 43 is engaged with the fixed stop 52. To start the machine in operation, the operator first 115 swings the free end of the tone arm over upon the record on the turntable so as to move the arm 43 to a position in front of the stud 27, which is permitted by the slot 26 in the disk 24, for as the arm 43 is moved away from the fixed stop 52 it engages the stud 27 and forces the disk 24 in the direction of the arrow 57, Fig. 1, until the arm 43 has cleared the stud 27 and passes in 120 front thereof, whereupon the disk 24 is returned to its normal position by the rod 23, which is sufficiently resilient to act as a spring. The return of the disk 24 to its normal position, places the stud 27 in the path of movement of the arm 43, whereupon 125

the operator turns the free end of the tone arm *c* toward the circumference of the record *b* to bring the stylus *d* into position to engage the record at its starting point.

6 This outward movement of the tone arm *c* causes the arm 43 to engage the stud 27 and to turn the disk 24 so as to disengage the brake 10 and release the turntable *a*, which is then rotated by its motor.

10 As soon as the brake is disengaged, it is locked in its inoperative or off position by the dog 33, as shown in Fig. 4, and remains in this position, until the stylus has reached the end of the record, at which time the

15 arm 43 engages the pin 40 on the lever 34, moves the latter to trip the locking dog 33 and allow the spring 29 to apply the brake as above described. The arm 43 may be adjusted by turning it on its pivot 51, so

20 as to position it with relation to the tone arm, so that the arm 43 may trip the locking dog 33 and allow the brake to be applied to the turntable when the stylus *d* reaches a predetermined position over the

25 turntable, which enables records of different sizes or diameters to be used on the machine and have the brake applied and the machine stopped when the stylus reaches the end of each record, and which also permits

30 the machine to be stopped, if so desired, when the stylus reaches predetermined points of the same record.

From the above description, it will be seen that the brake is applied to the turn-

35 table when the end of the tone arm which carries the stylus is beyond or outside of the record, and that the brake is released from the turntable by moving the free end of the tone arm inwardly over the record to a position beyond the starting position for the

40 stylus and then outwardly into the starting position. It will further be noticed that when the tone arm is in its starting position, the brake is locked in its released or inop-

45 erative position.

It will also be noticed that when the stylus reaches the end of the record, the

50 brake is unlocked by the device on the tone arm and is automatically applied to the

turntable to stop the same.

It will further be noticed that the device movable with the tone arm effects the release of the brake in order to start the machine and also effects two applications of the

55 brake, one application taking place when the stylus reaches the end of the record, and the other when the stylus is beyond the starting position of the stylus and tone arm.

It is not desired to limit the invention to

60 the particular embodiment thereof which is herein shown.

Claims:

1. In a machine of the character de-

scribed, in combination, a turntable, a tone

65 arm cooperating therewith, a brake mem-

ber cooperating with said turntable, a slide-
able bar connected with said brake member,
a spring to move said bar to apply the brake
member to the turntable, a catch on said
bar, a locking dog cooperating with said
70 catch, a lever to which said locking dog is
connected, a collar mounted on said tone
arm and provided with an arm to effect
movement of the slideable bar in one direc-
tion to release the brake member and to un-
lock said slideable bar and permit said spring
75 to move it and apply the brake member.

2. In a machine of the character de-
scribed, in combination, a turntable, a tone
arm cooperating therewith, a brake member
cooperating with said turntable, mechanism
80 for moving said brake member in one direc-
tion to disengage it from said turntable,
means for moving the brake member in the
opposite direction, to engage it with the
turntable, means for locking the brake mem-
ber in its disengaged position, and a device
85 governed by the tone arm for actuating the
locking means and adjustable into different
positions with relation to said locking
means.

3. In a machine of the character de-
scribed, in combination, a turntable, a tone
arm cooperating therewith, a brake for said
turntable, mechanism for actuating said
90 brake, and a device movable with said tone
arm for controlling said brake actuating
mechanism to release and apply the brake
by movement of the tone arm into the dif-
ferent positions in the same direction.

4. In a machine of the character de-
scribed, in combination, a turntable, a tone
arm co-operating therewith, a brake for said
turntable, mechanism for operating said
brake and a device movable with the tone
100 arm and adjustable to enable the brake to be
applied at different points in the movement
of the tone arm.

5. In a machine of the character de-
scribed, in combination, a turntable, a tone
arm cooperating therewith, a brake for said
turntable, and means controlled by the tone
arm for releasing the brake by movement of
the tone arm in one direction and for apply-
110 ing the brake by further movement of the
tone arm in the same direction.

6. In a machine of the character de-
scribed, in combination, a turntable, a tone
arm cooperating therewith, a brake for said
turntable, mechanism for actuating said
115 brake, a locking device cooperating with
said actuating mechanism to lock the brake
in its inoperative position, and a device
movable with said tone arm and cooperating
with said actuating mechanism for releas-
ing the brake by movement of the tone arm
120 in one direction and also cooperating with
said locking device when the tone arm is
moved in the opposite direction to effect the
application of said brake.

- 4
7. In a machine of the character described, in combination, a turntable, a tone arm cooperating therewith, a brake member cooperating with said turntable, a ⁵ slideable bar connected with said brake member, a spring to move said bar to apply the brake member to the turntable, a rotatable disk to

which said slideable bar is connected, and a device movable with said tone arm cooperating with said disk to turn it and release ¹⁰ said brake.

In testimony whereof, I have signed my name to this specification.

ANTONIO REA.
